Corporation, New Haven, Conn., a corporation
of Connecticut

Application September 27, 1950, Serial No. 12,369

Term of patent 14 years

(Cl. D52—2)

To all whom it may concern:

Be it known that we, Henry M. Dunn and David Oles, citizens of the United States, residing at New Haven, in the county of New Haven and State of Connecticut, have invented a new, original, and ornamental Design for an Oil-Changing Apparatus for Automobiles and the Like, of which the following is a specification, reference being had to the accompanying drawing, forming part thereof.

Fig. 1 is a perspective view of an oil-changing apparatus for automobiles and the like as seen from the front and showing our new design;

Fig. 2 is a side elevation thereof; and

Fig. 3 is a top plan view thereof.

We claim:

The ornamental design for an oil-changing apparatus for automobiles and the like, substantially as shown.

HENRY M. DUNN.
DAVID OLES.
